ABSTRACT: A detergent composition comprising a compound having the formula:

wherein:

- (1) R_1 is a straight or branched higher alkyl group of C_6 to C_{30} , and preferably C_{10} to C_{22} ;
- (2) R_2 is a straight or branched alkyl of C_3 to C_{12} , and preferably C_3 to C_6 ;
- (3) R_3 to R_7 are, independently, hydrogen or straight or branched alkyl of C_1 to C_{10} , and preferably hydrogen or lower alkyl of C_1 to C_4 ;
- (4) Z is oxygen ($-\text{O}-$) or sulfur ($-\text{S}-$);
- (5) x and y have the values 0 to 1 and $x+y=1$; and
- (6) M is a cation such as hydrogen, alkali metal, ammonium, substituted ammonium or amine and preferably a water-solubilizing, salt-forming group. The hydroxy oxa (or thia) sulfonates of the detergent composition provide both detergency and fabric softening characteristics and are hereinafter referred to generally as hydroxy ether sulfonates.

**BUILT DETERGENT COMPOSITIONS CONTAINING
HYDROXY ETHER SULFONATES**

The present invention is directed to novel detergent compositions, and more particularly, to novel detergent compositions based upon hydroxy ether sulfonates and water-soluble alkaline detergency builder salts.

In recent years, many detergent compositions have been formulated based upon linear alkyl benzene sulfonates, compounds thought to possess the best detergency characteristics. While such anionic detergents do possess excellent detergency characteristics, the use of linear alkyl benzene sulfonates and other anionic detergents based upon the alkyl aryl sulfonate has certain distinct shortcomings.

Since the alkyl aryl sulfonates or linear alkyl benzene sulfonates do not possess any fabric-softening characteristics, it is necessary to employ an additional fabric softener when employing such anionic detergents. Since however, the best fabric softeners produced to date are of the cationic quaternary ammonium type, such fabric softeners cannot be formulated in the same detergent composition with the anionic detergent. Thus, the conjoint employment of the anionic detergent and the cationic fabric softener is precluded since such fabric softeners and detergents complex and precipitate when employed conjointly thereby eliminating the functional characteristics of each of the materials. Accordingly, it has been found necessary to employ the quaternary ammonium fabric softener in the the rinse cycle of the fabric-washing process so that no contact between the anionic detergent and the cationic fabric softener will occur. This of course provides a great inconvenience in textile washing since it necessitates the addition of active ingredients at two separate points in the washing cycle.

Additionally, conventional anionic detergents based upon linear alkyl benzene sulfonates or alkyl aryl sulfonates in general possess the undesirable characteristics of phase incompatibility with various water-soluble alkaline detergent builders in aqueous systems. Thus, the anionic detergents are incompatible with various phosphate builders generally employed in detergent compositions thereby eliminating the all purpose functionality of the detergents. Accordingly, a clear single-phase liquid detergent composition cannot be prepared from the conventional phosphate builders and the linear alkyl benzene sulfonate detergents since a separation of phases usually results.

Accordingly, it has long been the desire of the detergent industry to develop a detergent composition possessing detergency and fabric-softening characteristics and compatibility with conventional water-soluble alkaline detergency builder salts.

It has now been discovered in accordance with the present invention that detergent compositions comprising certain hydroxy ether sulfonates in conjunction with water-soluble alkaline detergency builder salts possess all of the characteristics desired. Thus, in this respect it has been discovered that the active hydroxy ether sulfonate possesses not only exceptional detergency characteristics, but also possesses fabric-softening characteristics and is completely compatible with conventional water-soluble alkaline detergency builder salts. Thus, the combination of the present invention comprising the hydroxy ether sulfonates and the conventional water-soluble alkaline detergency builder salts can be produced both as a homogeneous single-phase liquid detergent composition or can be conveniently prepared in the form of bars, flakes, granular or tableted granular compositions.

Accordingly, it is a principal object of the present invention to provide novel detergent compositions which eliminate the inherent deficiencies of previously employed compositions.

A further object of the present invention is to provide novel detergency compositions wherein the detergent component thereof possesses, in addition to detergency characteristics, fabric-softening characteristics, and is completely compatible with conventional water-soluble alkaline detergency builder salts.

A still further object of the present invention is to provide a novel detergent composition comprising certain detergents and fabric-softening hydroxy ether sulfonates in combination with water-soluble alkaline detergency builder salts.

Still further objects and advantages of the novel detergent composition of the present invention will become more apparent from the following more detailed description thereof.

In accordance with the present invention, it has now been discovered that certain hydroxy ether sulfonates possess the unusual characteristics of excellent detergency and fabric-softening ability in addition to complete compatibility with water-soluble alkaline detergency builder salts conventionally employed in detergent compositions. Accordingly, the present invention is directed to such detergent compositions based upon hydroxy ether sulfonates and water-soluble alkaline detergency builder salts.

THE HYDROXY ETHER SULFONATE COMPONENT

The hydroxy ether sulfonates employed in the novel detergent compositions of the present invention possess both detergency characteristics and fabric softening ability and correspond to the general formula:

wherein:

1. R_1 is straight or branched higher alkyl group of C_6 to C_{30} , and preferably C_{10} to C_{22} ;
2. R_2 is a straight or branched alkyl of C_3 to C_{12} , and preferably C_3 to C_6 ;
3. R_3 to R_7 are, independently, hydrogen or straight or branched alkyl of C_1 to C_{10} , and preferably hydrogen or lower alkyl of C_1 to C_4 ;
4. Z is oxygen ($-\text{O}-$) or sulfur ($-\text{S}-$);
5. x and y have the values 0 to 1 and $x+y=1$; and
6. M is a cation such as hydrogen alkali metal, ammonium, substituted ammonium or amine and preferably a water-solubilizing, salt-forming group. While the sodium salts of the hydroxy ether sulfonates of the present invention are preferred, it is, of course, possible to advantageously employ any water-solubilizing cation e.g. other alkali metals such as potassium or lithium. Additionally, ammonium and amine salts e.g., trialkanolamine salts such as triethanolamine can be advantageously employed with exceptional results.

The novel hydroxy ether sulfonates of the present invention are prepared by reacting an epoxy alkane with an unsaturated aliphatic alcohol with subsequent sulfonation of the reaction product. The epoxy alkane reactants that are useful in the preparation of the hydroxy ether sulfonates of the present invention can be any epoxy alkane having a terminal group i.e., an epoxy alkane having the structure:

wherein R_1 is as defined above. As noted above, R_1 comprises a straight or branched chain alkyl radical of from about six to about 30 carbon atoms. Illustrative examples of some suitable alkyl radicals include:

- n-hexyl
- iso-hexyl
- n-heptyl
- iso-heptyl

n-octyl	triethanol amine salt of 6-hydroxy-4-oxaeicosyl sulfonic acid
iso-octyl	8-hydroxy-6-oxahexadecyl sodium sulfonate
n-nonyl	8-hydroxy-6-oxaoctadecyl sodium sulfonate
iso-nonyl	8-hydroxy-6-oxaeicosyl sodium sulfonate
n-decyl	8-hydroxy-6-oxadocosyl sodium sulfonate
n-dodecyl	8-hydroxy-8 methyl-12-ethyl-6-oxapentadecyl sodium sulfonate
tert-dodecyl	8-hydroxy-11,11, dimethyl-6-oxahexadecyl sodium sulfonate
2-propylheptyl	8-hydroxy-6-oxaheptadecyl potassium sulfonate
5-ethylnonyl	8-hydroxy-6-oxanonadecyl potassium sulfonate
2-butyloctyl	8-hydroxy-6-oxaeicosyl potassium sulfonate
n-undecyl	8-hydroxy-6-oxauncosyl potassium sulfonate
n-tridecyl	8-hydroxy-11,11-dimethyl-6-oxahexadecyl potassium sulfonate
n-tetradecyl	8-hydroxy-6-oxatetracosyl potassium sulfonate
n-pentadecyl	8-hydroxy-6-oxahexadecyl lithium sulfonate
tert-octadecyl	8-hydroxy-6-oxadocosyl lithium sulfonate
2,6,8 -trimethylnonyl	8-hydroxy-6-oxahexadecyl ammonium sulfonate
7-ethyl-2 -methyl-4 -undecyl	8-hydroxy-6-oxadocosyl ammonium sulfonate
n-hexadecyl	8-hydroxy-8 methyl-12-ethyl-6-oxapentadecyl ammonium sulfonate
n-octadecyl	triethanol amine salt of 8-hydroxy-6-oxahexadecyl sulfonic acid
eicosyl	triethanol amine salt of 8-hydroxy-6-oxaelcosyl sulfonic acid
docosyl	triethanol amine salt of 8-hydroxy-9,9-dimethyl-6-oxahexadecyl sulfonic acid
tricosyl	7-hydroxy-5-oxahexadecyl sodium sulfonate
pentacosyl	7-hydroxy-5-oxadocosyl sodium sulfonate
triacontyl etc.	7-hydroxy-9,9-dimethyl-5-oxahexadecyl sodium sulfonate
The alkyl radicals may also include unsaturated alkyl radicals such as hexaryl, oleoyl, dodecenyl, hexadecenyl, and the like.	7-hydroxy-5-oxaoctadecyl potassium sulfonate
Illustrative examples of the epoxy alkanes which can be employed as reactants in the process of the present invention to produce the novel hydroxy ether sulfonates of the present invention include:	7-hydroxy-5-oxadocosyl potassium sulfonate
1,2 epoxyhexane	7-hydroxy-9,9-dimethyl-5-oxahexadecyl potassium sulfonate
1,2 epoxyoctane	7-hydroxy-5-oxaheptadecyl lithium sulfonate
1,2 epoxydecane	7-hydroxy-5-oxadocosyl lithium sulfonate
1,2 epoxyundecane	8-hydroxy-6-oxahexadecyl ammonium sulfonate
1,2 epoxydodecane	8-hydroxy-6-oxadocosyl ammonium sulfonate
1,2 epoxytridecane	8-hydroxy-8 methyl-12-ethyl-6-oxapentadecyl ammonium sulfonate
1,2 epoxytetradecane	triethanol amine salt of 8-hydroxy-9,9-dimethyl-5-oxahexadecyl sulfonic acid
1,2 epoxypentadecane	7-hydroxy-5-oxanonadecyl lithium sulfonate
1,2 epoxyhexadecane	7-hydroxy-8 methyl-12-ethyl-5-oxapentadecyl ammonium sulfonate
1,2 epoxyoctadecane	triethanol amine salt of 7-hydroxy-7,7-dimethyl-5-oxahexadecyl sulfonic acid
7-ethyl-2-methyl-1,2-epoxyundecane	10-hydroxy-8-oxahexadecyl sodium sulfonate
2,6,8-trimethyl-1,2-epoxynonane	10-hydroxy-8-oxaoctadecyl sodium sulfonate
1,1,2-trimethyl-1,2-epoxy decane	10-hydroxy-8-oxadocosyl sodium sulfonate
1,1-dimethyl-2-methyl-1,2-epoxytetradecane	10-hydroxy-7,7-dimethyl-8-oxahexadecyl sodium sulfonate
1,1-diethyl epoxy undecane	10-hydroxy-8-oxahexadecyl potassium sulfonate
1,1-diethyl epoxy decane	10-hydroxy-8-oxadocosyl potassium sulfonate
1,1-diisopropyl epoxy octane etc.	10-hydroxy-7,7-dimethyl-8-oxahexadecyl potassium sulfonate
Exemplary hydroxy ether sulfonates in accordance with the present invention include:	10-hydroxy-8-oxahexadecyl lithium sulfonate
6-hydroxy-4-oxahexadecyl sodium sulfonate	10-hydroxy-8-oxahexadecyl ammonium sulfonate
6-hydroxy-4-oxaheptadecyl sodium sulfonate	10-hydroxy-14 methyl-12-ethyl-8-oxapentadecyl ammonium sulfonate
6-hydroxy-4-oxaoctadecyl sodium sulfonate	triethanol amine salt of 10-hydroxy-7,7-dimethyl-8-oxahexadecyl sulfonic acid
6-hydroxy-4-oxaeicosyl sodium sulfonate	11-hydroxy-9-oxahexadecyl sodium sulfonate
6-hydroxy-4-oxadocosyl sodium sulfonate	11-hydroxy-9-oxaoctadecyl potassium sulfonate
6-hydroxy-8 -methyl-12-ethyl-4-oxapentadecyl sodium sulfonate	11-hydroxy-9-oxahexadecyl lithium sulfonate
6-hydroxy-7,7-dimethyl-4-oxahexadecyl sodium sulfate	11-hydroxy-8 methyl-12-ethyl-9-oxapentadecyl ammonium sulfonate
6-hydroxy-4 -oxahexadecyl potassium sulfonate	triethanol amine salt of 11-hydroxy-7,7-dimethyl-9-oxahexadecyl sulfonic acid
6-hydroxy-4-oxanonadecyl potassium sulfonate	12-hydroxy-10-oxahexadecyl sodium sulfonate
6-hydroxy-4-oxauncosyl potassium sulfonate	12-hydroxy-7,7-dimethyl-10-oxahexadecyl sodium sulfonate
6-hydroxy-8 -methyl-12-ethyl-4-oxapentadecyl potassium sulfonate	12-hydroxy-10-oxaoctadecyl potassium sulfonate
6-hydroxy-7,7-dimethyl-4-oxahexadecyl potassium sulfonate	12-hydroxy-10-oxahexadecyl lithium sulfonate
6-hydroxy-4-oxatetracosyl potassium sulfonate	12-hydroxy-10-oxahexadecyl ammonium sulfonate
6-hydroxy-4-oxahexadecyl lithium sulfonate	triethanol amine salt of 12-hydroxy-7,7-dimethyl-10-oxahexadecyl sulfonic acid
6-hydroxy-4-oxanonadecyl lithium sulfonate	15-hydroxy-13-oxahexadecyl sodium sulfonate
6-hydroxy-4-oxaheptadecyl ammonium sulfonate	15-hydroxy-7,7-dimethyl-13-oxahexadecyl sodium sulfonate
6-hydroxy-4-oxadocosyl ammonium sulfonate	15-hydroxy-13-oxadocosyl potassium sulfonate
6-hydroxy-8 methyl-12-ethyl-4-oxapentadecyl ammonium sulfonate	
triethanol amine salt of 6-hydroxy-4-oxahexadecyl sulfonic acid	

15-hydroxy-13-oxahexadecyl lithium sulfonate	5
15-hydroxy-8 methyl-12-ethyl-13-oxapentadecyl ammonium sulfonate	
triethanol amine salt of 15-hydroxy-7,7-dimethyl-13-oxahexadecyl sulfonic acid (2) wherein $y=0$ and $x=1$	5

DETERGENCY BUILDER SALTS

In addition to the active detergent and fabric-softening hydroxy ether sulfonate, the novel detergent compositions of the present invention contain one or more water-soluble detergency builder salts either of the organic or the inorganic type and preferably alkaline salts.

Examples of water-soluble inorganic detergency builder salts are alkali metal carbonates, phosphates, polyphosphates, sulfates, and silicates, etc. Specific examples of such salts are sodium, potassium and lithium tripolyphosphates, carbonates, pyrophosphates, orthophosphates and hexamethaphosphates, sodium, potassium and lithium sulfates and sodium, potassium and lithium silicates. Examples of organic alkaline detergency builder salts are (1) alkali metal aminopolycarboxylates [e.g., sodium and potassium ethylenediaminetetraacetates, N-(2-hydroxyethyl)-ethyl-enediaminetriacetates, nitrilo triacetates, and N-(2-hydroxyethyl)-nitrilo diacetates]; (2) alkali metal salts of phytic acid (e.g., sodium and potassium phytates—see U.S. Pat. No. 2,739,942); (3) water-soluble salts of ethane-1-hydroxy-1,1-diphosphonate (e.g., the trisodium and tripotassium salts—see U.S. Pat. No. 3,159,581); (4) water-soluble salts of methylene diphosphonic acid (e.g., trisodium and tripotassium methylene diphosphonate and the other salts described in U.S. Pat. No. 2,213,030); (5) water-soluble salts of substituted methylene diphosphonic acids (e.g., trisodium and tripotassium ethylidene, isopropylidene, benzylmethyldene, and halomethylidene diphosphonates); (6) water-soluble salts of polycarboxylate polymers and copolymers (e.g., homopolymers of itaconic acid, aconitic acid; maleic acid; mesaconic acid; fumaric acid; methylene malonic acid; and citric acid and copolymers thereof with other compatible copolymerizable monomers such as ethylene); and mixtures thereof.

DETERGENT COMPOSITION

In the detergent compositions of the present invention the active hydroxy ether sulfonate is generally employed in an amount of from about 1 to about 90 percent by weight of the total composition, while the water-soluble detergency builder salts comprise from about 10 to about 99 percent by weight of the total composition. Preferably, the hydroxy ether sulfonate comprises about 5-50 percent by weight while the detergent builders comprise from 15-90 percent of the total composition. Generally, the ratio of the water-soluble detergency builder salts to the total detergent is in the range of 1:3 to 20:1.

The compositions of this invention may be formulated as liquids, solids, pastes, gels, etc. As liquids using water or the vehicle, the compositions are unexpectedly, characterized by unique clarity and homogeneity i.e. the compositions are single-phase systems.

The detergent compositions of this invention can contain any of the usual compatible adjuvants, diluents and additives including other detergents, for example, anionic nonionic, amphotolytic, cationic or zwitterionic detergents; perfumes, antitarnishing agents, antiredeposition agents, bacteriostatic agents, dyes, fluorescers, suds builders, suds depressors, and

the like, without detracting from the advantageous properties of the composition.

Suitable anionic surface active agents include those surface-active or detergent compounds which contain an organic hydrophobic group and an anionic solubilizing group. Typical examples of anionic solubilizing groups are sulfonate, sulfate, carboxylate, phosphonate and phosphate. Examples of suitable anionic detergents which fall within the scope of the invention include the soaps, such as the water-soluble salts of higher fatty acids or rosin acids, such as may be derived from fats, oils and waxes of animal, vegetable or marine origin, e.g. the sodium soaps of tallow, grease, coconut oil, tall oil and mixtures thereof, and the sulfated and sulfonated synthetic detergents, particularly those having about eight to 26, and preferably about 12-22, carbon atoms to the molecule.

As examples of suitable synthetic anionic detergents there may be cited the higher alkyl mononuclear aromatic sulfonates such as the higher alkyl benzene sulfonates containing from 10 to 16 carbon atoms in the alkyl group in a straight or branched chain, e.g., the sodium salts of higher alkyl benzene sulfonates or of the higher alkyl toluene, xylene and phenol sulfonates; alkyl naphthalene sulfonate, ammonium diethyl naphthalene sulfonate, and sodium dinonyl naphthalene sulfonate. In one preferred type of composition there is used a linear alkyl benzene sulfonate having a high content of 3- (or higher) phenyl isomers and a correspondingly low content (well below 50 percent of 2- (or lower) phenyl isomers; in other terminology, the benzene ring is preferably attached in large part at the 3 or higher (e.g. 4, 5, 6 or 7) position of the alkyl group and the content of isomers in which the benzene ring is attached at the 2 or 1 position is correspondingly low. Particularly preferred materials are set forth in U.S. Pat. No. 3,320,174, May 16, 1967, of J. Rubinfeld.

The mixtures containing linear alkylbenzene sulfonates and the detergent compounds of this invention have unexpectedly good properties, particularly with respect to softening power. These mixtures are the invention of Harold Wixon.

Other anionic detergents are the olefin sulfonates, including long-chain alkene sulfonates, long-chain hydroxy-alkane sulfonates or mixtures of alkenesulfonates and hydroxyalkanesulfonates. These olefin sulfonate detergents may be prepared, in known manner, by the reaction of SO_3 with long chain olefins (of 8-25, preferably 12-21 carbon atoms) of the formula $\text{R}'\text{CH}=\text{CHR}''$, where R' is alkyl and R'' is alkyl or hydrogen, to produce a mixture of sultones and alkenesulfonic acids, which mixture is then treated to convert the sultones to sulfonates. Examples of other sulfate or sulfonate detergents are paraffin sulfonates, such as the reaction products of alpha olefins and bisulfites (e.g. sodium bisulfite), e.g., primary paraffin sulfonates of about 10-20, preferably about 15-20, carbon atoms; sulfates or higher alcohols; salts of α -sulfocatty esters (e.g. of about 10-20 carbon atoms, such as methyl α -sulfonyristate or α -sulfotallowate).

Examples of sulfates of higher alcohols are sodium lauryl sulfate, sodium tallow alcohol sulfate, Turkey Red Oil or other sulfated oils, or sulfates of mono- or di-glycerides of fatty acids (e.g. stearic monoglyceride monosulfate), alkyl poly (ethenoxy) ether sulfates such as the sulfates of the condensation products of ethylene oxide and lauryl alcohol (usually having one to five ethenoxy groups per molecule); lauryl or other higher alkyl glyceryl ether sulfonates; aromatic poly (ethenoxy) ether sulfates such as the sulfates of the condensation products of ethylene oxide and nonyl phenol (usually having one to six oxyethylene groups per molecule).

The suitable anionic detergents include also the acyl sarcosinates (e.g. sodium lauroylsarcosinate) the acyl esters (e.g. oleic acid ester) of isethionates, and the acyl N-methyl taurides (e.g. potassium N-methyl lauroyl- or oleyl tauride).

The most highly preferred water soluble anionic detergent compounds are the ammonium and substituted ammonium (such as mono-, di- and triethanolamine), alkali metal (such as sodium and potassium) and alkaline earth metal (such as calcium and magnesium) salts or the higher alkyl benzene sul-

fonates, olefin sulfonates, the higher alkyl sulfates, and the higher fatty acid monoglyceride sulfates. The particular salt will be suitably selected depending upon the particular formulation and the proportions therein.

5 Nonionic surface active agents include those surface active or detergent compounds which contain an organic hydrophobic group and a hydrophilic group which is a reaction product of solubilizing group such as carboxylate, hydroxyl, amide or amino with ethylene oxide or with the polyhydration product thereof, polyethylene glycol.

As examples of nonionic surface active agents which may be used there may be noted the condensation products of alkyl phenols with ethylene oxide, e.g., the reaction product of isooctyl phenol with about six to 30 ethylene oxide units; condensation products of alkyl thiophenols with 10 to 15 ethylene oxide units; condensation products of higher fatty alcohols such as tridecyl alcohol with ethylene oxide; ethylene oxide adducts of monoesters of hexahydric alcohols and inner ethers thereof such as sorbitan monolaurate, sorbitol monoleate and mannitol monopalmitate, and the condensation products of polypropylene glycol with ethylene oxide. Other nonionics include amine oxides, e.g. lauryl dimethyl amine oxide; sulfoxides and the like.

15 Cationic surface-active agents may also be employed. Such agents are those surface active detergent compounds which contain an organic hydrophobic group and a cationic solubilizing group. Typical cationic solubilizing groups are amine and quaternary groups.

20 30 As examples of suitable synthetic cationic detergents there may be noted the diamines such as those of the type $\text{RNHC}_2\text{H}_4\text{HN}_2$ wherein R is an alkyl group of about 12 to 22 carbon atoms, such as N-2-aminoethyl stearyl amine and N-2-aminoethyl myristyl amine; amide-linked amines such as those

25 of the type $\text{R}'\text{CONHC}_2\text{H}_4\text{NH}_2$ wherein R' is an alkyl group of about nine to 20 carbon atoms, such as N-2-amino ethylstearyl amide and N-amino ethyl myristyl amide; quaternary ammonium compounds wherein typically one of the groups linked to the nitrogen atom is an alkyl group of about 12 to 18 carbon

30 atoms and three of the groups linked to the nitrogen atom are alkyl groups which contain one to three carbon atoms, including such one to three carbon alkyl groups bearing inert substituents, such as phenyl groups, and there is present an anion such as halogen, acetate, methosulfate, etc. Typical quaternary ammonium detergents are ethyl-dimethyl-stearyl ammonium chloride, benzyl-dimethyl-stearyl ammonium chloride, benzyl-dimethyl-stearyl ammonium chloride, trimethyl stearyl ammonium chloride, trimethyl-cetyl ammonium bromide, dimethyl-ethyl dilauryl ammonium chloride, dimethyl-propyl-myristyl ammonium chloride, and the corresponding methosulfates and acetates.

35 Examples of suitable amphoteric detergents are those containing both an anionic and a cationic group and a hydrophobic organic group, which is advantageously a higher aliphatic radical, e.g. of 10-20 carbon atoms. Among these are the N-long chain alkyl aminocarboxylic acids (e.g. of the formula

40 45 50 55 60 65 70 75 ; the N-long chain alkyl iminodicarboxylic acids (e.g. of the formula $\text{RN}(\text{R}'\text{COOM})_2$) and the N-long chain alkyl betaines (e.g. of the formula

70 75) where R is a long chain alkyl group, e.g. of about 10-20 carbons, R' is a divalent radical joining the amino and carboxyl portions of an amino acid (e.g. an alkylene radical of 1-4 carbon atoms), M is hydrogen or a salt-forming metal, R^2 is a hydrogen or another monovalent substituent (e.g. methyl or

other lower alkyl), and R³ and R⁴ are monovalent substituents joined to the nitrogen by carbon-to-nitrogen bonds (e.g. methyl or other lower alkyl substituents). Examples of specific amphoteric detergents are N-alkyl-beta-aminopropionic acid; N-alkyl-beta-iminodipropionic acid, and N-alkyl, N,N-dimethyl glycine; the alkyl group may be, for example, that derived from coco fatty alcohol, lauryl alcohol, myristyl alcohol (or a lauryl-myristyl mixture), hydrogenated tallow alcohol, cetyl, stearyl, or blends of such alcohols. The substituted aminopropionic and iminodipropionic acids are often supplied in the sodium or other salt forms, which may likewise be used in the practice of this invention. Examples of other amphoteric detergents are the fatty imidazolines such as those made by reacting a long-chain fatty acid (e.g. of 10 to 20 carbon atoms) with diethylene triamine and monohalocarboxylic acids having two to six carbon atoms, e.g. 1-coco-5-hydroxyethyl-5-carboxymethylimidazoline; betaines containing a sulfonyc groups instead of the carboxylic group; betaines in which the long-chain substituent is joined to the carboxylic group without an intervening nitrogen atom, e.g. inner salts of 2-trimethylamino fatty acids such as 2-trimethylaminolauric acid, and compounds of any of the previously mentioned types but in which the nitrogen atom is replaced by phosphorus.

While the detergent compositions of the present invention are excellent compositions for all types of cleaning operations, they are extremely effective for the cleaning of textiles in a conventional laundry or washing machine. Thus, the detergent compositions of the present invention can be effectively used for laundering fabrics in water having a temperature from about 60° F. to about 212° F., the detergent composition of the present invention exhibiting unusually effective detergency and fabric softening characteristics in both cold and hot water. Preferably, the step of the present invention is followed by rinsing and drying of the fabric. The detergent composition concentration in the wash solution should range from about 0.05 percent to about 0.5 percent by total weight, and the detergent composition should be added so as to provide an effective detergent and softening amount of the hydroxy ether sulfonate component of at least 0.002 percent.

In washing fabrics, the addition of the fabrics and the detergent composition can be conducted in any suitable conventional manner. Thus, for example the fabrics can be added to the container or washer either before or after the washing solution is added. The fabrics are then agitated in the detergent solution for varied periods of time, a wash cycle of from 8 to 15 minutes being generally used in the washing cycle of an automatic agitator type washer. As stated above, following the washing of the fabrics the detergent composition is drained off and the fabrics are rinsed in substantially pure water. Here again, as a matter of choice, the fabrics can be rinsed as many times as desired. After rinsing of the fabrics, they are dried, first by spinning, and then by contact with the air as in a conventional hanging of the fabrics on a clothesline or in an automatic dryer type system.

In the preparation of the novel detergent compositions of the present invention, generally, the organic detergent and fabric-softening component as well as the builders and any minor ingredients are incorporated into the composition prior to its conversion into the final product form e.g. detergent granulated, flakes, bar etc. However, the individual components of the novel detergent composition of the present invention can be added in the form of particles or directly as a liquid to produce a liquid detergent composition.

A particularly preferred detergent composition of the present invention comprises the hydroxy ether sulfonate detergent and softener component in combination with sodium xylene sulfonate and potassium pyrophosphate in a clear, aqueous single-phase liquid form. In such a liquid detergent composition the water generally comprises from about 30 to about 70 percent of the total composition while the hydroxy ether sulfonate comprises from about 5 to 15 percent by weight; the sodium xylene sulfonate from 5 to 15 percent by weight and the potassium pyrophosphate or similar alkaline detergency builder salt from about 10 to 30 percent by weight.

While the above description of the present invention has been described primarily with respect to the combination of the hydroxy ether sulfonate detergent and fabric softening component with a water soluble alkaline detergency builder salt, it is important to note that where the washing of very fine fabrics is to be encountered, the detergency builder salts can be eliminated from the composition. Thus, with respect to the preferred composition noted above a composition adapted for the washing of fine fabrics can comprise the hydroxy ether sulfonates with or without sodium xylene sulfonate in an aqueous, single phase system.

The following specific examples illustrate various embodiments of the present invention. It is to be understood however, that such examples are presented for purposes of illustration only and the present invention is in no way to be deemed as limited thereby.

EXAMPLE I

- 20 An experiment is conducted in order to demonstrate the compatibility of the hydroxy ether sulfonate detergent and fabric softener with water soluble alkaline detergency builder salts.
- 25 A composition comprising 15 percent by weight of 6-hydroxy-4-oxaeicosyl sodium sulfonate, 35 percent sodium tripolyphosphate, and 50 percent sodium sulfate is prepared by mixing respectively 3.75 grams, 8.75 grams, and 12.50 grams of the individual components. 25 grams of a powdered composition is prepared.
- 30 This powdered composition comprising the hydroxy ether sulfonate, sodium tripolyphosphate and sodium sulfate is added to 175 grams of water thereby preparing a total of 200 grams of solution. This solution is a clear single phase liquid at room temperature.
- 35 An attempt is made to prepare a clear single-phase liquid detergent composition employing a linear tridecyl benzene sulfonate slurry in lieu of the hydroxy ether sulfonate above. A homogeneous single-phase liquid detergent can not be prepared but the composition produced is opaque
- 40 with granular detergent particles which separate rapidly. Dilution of the composition to 500 grams with additional water does not change the composition and detergent particles still separate rapidly.
- 45 This therefore clearly shows the unusual and unexpected compatibility of the hydroxy ether sulfonate detergent and fabric softener with water-soluble alkaline detergency builder salts.
- 50 A further detergent composition in accordance with the present invention is prepared from the following components.

Component	Percent By Weight
55 6-hydroxy-4-oxaeicosyl sodium sulfonate potassium pyrophosphate solution, 60% water	10.0 25.0 65.0

60 Again, the liquid detergent composition is a viscous, single-phase, clear solution at room temperature.

65 The preparation of a similar composition is attempted employing a linear C13 alkyl benzene sulfonate in lieu of the hydroxy ether sulfonate employed in the compositions of the present invention. An incompatible two-layer liquid composition results when the water, linear alkyl benzene sulfonate, and potassium pyrophosphate solution are mixed.

70 Again, this illustrates the unexpectedly superior compatibility of the hydroxy ether sulfonate detergents and fabric softeners employed in the compositions of the present invention with water-soluble alkaline detergency builder salts.

EXAMPLE II

The detergency of the compositions of the present invention compared with a conventional detergent composition is tested

in a Spangler Soil (Sebum) detergency test in a tergotometer having normal reciprocating agitation. The test conditions employ three soiled swatches of fabric with 1000 milliliters of detergent solution, the detergent concentration being 0.15 percent in all cases.

The tests are run in both hard and soft water and both under cold-water and hot-water conditions.

In all cases, the detergent composition contains 50 percent sodium sulfates, 35 percent sodium tripolyphosphate, and 15 percent of the sulfonate detergent. Three tests are made employing a hydroxy ether sulfonate while a present run is made employing a linear tridecyl benzene sulfonate, a conventional anionic detergent.

After washing, rinsing and drying, the amount of lipid soil remaining on the swatches is determined, this amount being measured against the amount of soil on the swatches prior to washing. Accordingly, higher positive values indicate greater washing efficiency.

The detergent compositions embodied by the present invention are prepared as in example I above by the mere addition of the three active components to an aqueous system, the compatibility of the components providing a clear single phase liquid detergent composition. A dual-phase system is prepared in order to provide a liquid detergent composition comprising a linear tridecyl benzene sulfonate as the active detergent component since, such anionic detergent is found to be incompatible with the alkaline detergency builder salts and thus a clear single phase solution can not be prepared. Accordingly, the control system is prepared by providing separate aqueous solutions of (1) the linear tridecyl benzene sulfonate, xylene and water, and (2) sodium tripolyphosphate, sodium xylene sulfonate, and water.

The results of the detergent tests are shown in table I below:

TABLE I

	6-hydroxy-4-oxahexadecyl sulfonate, Na	6-hydroxy-4-oxaeicosyl sulfonate, Na	6-hydroxy-4-oxadocosyl sulfonate, Na	Linear tridecyl benzene sulfonate, Na
70° F., NB tap water	+17.6	+20.5	+19.6	+18.1
70° F., 300 p.p.m. water	+11.2	+18.0	+14.9	+9.5
120° F., NB tap water	+17.4	+20.2	+20.8	+20.1
120° F., 300 p.p.m. water	+12.8	+16.1	+15.9	+11.4

The results above clearly show that the hydroxy ether sulfonates of the present invention exhibit unusually good detergency in both hard and soft water under both hot and cold conditions. Accordingly, the compatible hydroxy ether sulfonate detergents and fabric softeners employed in the detergent compositions of the present invention not only possess the desirable detergency and fabric-softening characteristics as well as the compatibility with water soluble alkaline detergency builder salts, but, in addition, possess detergency characteristics substantially equal to or better than a conventional anionic detergent.

EXAMPLE III

A novel detergent composition of the present invention is tested for softening ability against a conventional anionic build detergent system. The composition of the present invention employed in the softening test is as follows:

6-hydroxy-4-oxaeicosyl sulfonate, sodium salt	10.0%
Sodium xylene sulfonate, 40% Al solution	20.0%
Potassium pyrophosphate, 60% Al solution	25.0%
Water	45.0%
	100.0%

The composition is prepared as in example I by blending the individual components and heating until a clear single phase liquid composition is formed. The clarity and homogeneity of the systems are maintained upon cooling to room temperature. The single-phase liquid composition has a specific gravity of 1.19, a pH of 9.9, and a viscosity of 20 cps.

A similar liquid composition is prepared by employing an

equivalent amount of linear dodecyl benzene sulfonate, a conventional anionic detergent, in lieu of the 6-hydroxy-4-oxaeicosyl sulfonate, sodium salt of the present invention. Here again, because of the incompatibility of the anionic detergent with the water-soluble alkaline detergency builder salts, the system is produced as two separate phases.

A fabric softening test is conducted by washing a terry-cloth towel in 17 gallons of N-B tap water at 120° F. employing 140 grams of the liquid detergent compositions. On a scale of softness wherein 1 designates no softening and 10 designates excellent softening, the composition of the present invention employing the hydroxy ether sulfonate of example I in conjunction with the alkaline detergency builder salts provides a softness rating of 9, while the comparable system containing a conventional linear dodecyl benzene sulfonate detergent rates 1.

This test therefore indicates the exceptional fabric softening ability of the hydroxy ether sulfonate detergents employed in the built detergent compositions of the present invention.

EXAMPLE IV

The following are typical detergent compositions in accordance with the present invention.

SOLID

Component	Percent
6-hydroxy-4-oxaeicosyl sodium sulfonate	9
Sodium tripolyphosphate	48
Sodium sulfate	32.8
Fluorescent dye	0.18
Perfume	0.02
Water	10

SOLID

Component	Percent
6-hydroxy-4-oxadocosyl sodium sulfonate	17
Sodium tripolyphosphate	30
Sodium sulfate	38.8
Sodium silicate (Na ₂ O:SiO ₂ = 1:2.35)	4
Brightener	0.4
Perfume	0.16
Water	10

SOLID

CMC	0.5
Fluorescent dye	0.8
PVA	0.5
Perfume	0.6
Sodium sulfate	53.4
Water	Balance

In each case the detergent composition, whether solid or liquid, was found to have an exceptional fabric-softening ability and detergent characteristics.

EXAMPLE V

Novel detergent compositions of the present invention were formulated as in example IV employing as the hydroxy ether sulfonate:

- 6-hydroxy-4-thiahexadecyl sodium sulfonate
- 6-hydroxy-oxaeicosyl sodium sulfonate
- 6hydroxy-7,7-dimethyl-4-oxahexadecyl potassium sulfonate
- 6-hydroxy-4-oxyaheptadecyl ammonium sulfonate
- 7-hydroxy-9,9-dimethyl-5-oxahexadecyl potassium sulfonate
- 8-hydroxy-6-oxanonadecyl potassium sulfonate
- Triethanolamine salt of 8-hydroxy-9,9-dimethyl-6-oxahexadecyl sulfonic acid
- 10-hydroxy-8-oxahexadecyl lithium sulfonate
- 12hydroxy-10-oxahexadecyl ammonium sulfonate

In each case the detergent composition, whether solid or liquid, was found to have an exceptional fabric softening ability and detergent characteristics.

EXAMPLE VI

Novel detergent compositions of the present invention were formulated as in Example IV employing as the hydroxy ether sulfonate;

- 15-hydroxy-13-oxahexadecyl sodium sulfonate
- 5hydroxy methyl-8-methyl
- 12-ethyl-4-oxapentadecyl ammonium sulfonate
- 6-hydroxymethyl-5-oxahexadecyl lithium sulfonate
- 5-hydroxymethyl-7-oxahexadecyl sodium sulfonate

methyl-5-hydroxymethyl-4-oxadocosyl potassium sulfonate
10-t-butyl-10-(hydroxymethyl)-9-oxahexadecyl sodium sulfonate
6-gamma-hydroxypropyl-5-oxahexadecyl sodium sulfonate
7-(delta-hydroxybutyl)-6-oxahexadecyl sodium sulfonate
6-isopropyl-5-hydroxyisopropylidene

In each case the detergent composition, whether solid or liquid, was found to have an exceptional fabric-softening ability and detergent characteristics.

EXAMPLE VII

Novel detergent compositions of the present invention were formulated as in example IV employing as the hydroxy ether sulfonate:

- 8-hydroxy-6-thianonadecyl potassium sulfonate
- 15-hydroxy-8 methyl-12-ethyl-13-thiapentadecyl ammonium sulfonate

- 7-hydroxymethyl-6thiahexadecyl ammonium sulfonate
- 8-isopropyl, 8-hydroxymethyl-7-thiahexadecyl lithium sulfonate

- 5-hydroxyisopropylidene-4-thiahexadecyl sodium sulfonate
- 5-methyl 5-(beta-hydroxyethyl)-4-thiaeicosyl sodium sulfonate

- 10-hydroxy-9-butyl-8-thiaoctadecyl potassium sulfonate

In each case the detergent composition, whether solid or liquid, was found to have an exceptional fabric-softening ability and detergent characteristics.

What is claimed is:

1. A detergent composition consisting essentially of:
A. a hydroxy ether sulfonate having the following formula

wherein:

1. R₁ is a straight or branched higher alkyl group of C₆ to C₃₀;
2. R₂ is a straight or branched alkylene of C₃ to C₁₂;
- 3R₃ to R₇ are, independently, hydrogen, straight or branched alkyl of C₁ to C₁₀;
4. Z is oxygen or sulfur;
5. x and y have the values of 0 to 1 and x+y=1; and
- 6 when x equals 0 the depicted OH group is attached directly to C⁺;
7. M is a water-solubilizing salt-forming cation, and

- B. a water soluble detergency builder salt the ratio of (A) to (B) ranging from 3:1 to 1:20.

2. The detergent composition of claim 1 wherein R₁ contains from about 10 to about 22 carbon atoms.

3. The detergent composition of claim 1 wherein R₂ contains from three to six carbon atoms.

4. The detergent composition of claim 1 wherein the hydroxy ether sulfonate is present in an amount of from about 1 to about 90 percent by weight.

5. The detergent composition of claim 4 wherein the hydroxy ether sulfonate is present in an amount from about 5 to about 50 percent by weight.

6. The composition of claim 1 wherein the hydroxy ether sulfonate is 6-hydroxy-4-oxaeicosyl sodium sulfonate.

7. The composition of claim 1 wherein the builder is potassium pyrophosphate.

8. The detergent composition of claim 1 including a hydrotrope.

9. The composition of claim 8 wherein the hydrotrope is xylene sulfonate.

10. The composition of claim 9 wherein the builder salt is potassium pyrophosphate.

11. The composition of claim 10 wherein the hydroxy ether sulfonate is 6-hydroxy-4-oxaeicosyl sodium sulfonate.
